GILBERT S. VERNAM, OF RIVER EDGE, NEW JERSEY, ASSIGNOR TO INTERNATIONAL COMMUNICATIONS LABORATORIES, INC., OF NEW YORK, N. Y., A CORPORATION OF NEW YORK

AUTOMATIC TELEGRAPH SWITCHING SYSTEM

Application filed July 23, 1930. Serial No. 470,007.

This invention relates in general to a telegraph exchange system and particularly to an automatic printing telegraph exchange system for facilitating telegraph communication, in either direction, between a plurality of customers' stations and a central telegraph station.

The objects of this invention are to provide means by which a customer can select one of a number of classes of telegraphic service furnished by a central telegraph station; to provide means by which the calls for any particular class of service will be confined to the first idle printer in a group furnishing that class of service; to provide means under control of a central station operator alone for releasing an established connection between a customer's station and the central station, and to provide means for controlling the printer motor at a calling or called subscriber's station.

The preferred embodiment of the present invention is shown in the accompanying drawings in which,

25 Figure 1 shows the system schematically.

Figs. 2 and 3 show the outward circuit, or the circuit from the calling central station to the called customer's station.

Fig. 4 shows the primary line finders of 30 the inward circuit, or the circuit from the calling customer's station to the called central station operator.

Fig. 5 shows the selecting circuits, the secondary line finders and the central station receiving operator's set associated with the 35 inward circuit.

Fig. 6 shows the wiring arrangement for starting the first idle secondary line finder.

The complete inward circuit is shown 40 when a subscriber's station as 52A, Fig. 2, is associated with line 51, Fig. 4, and Fig. 5 is placed to the right of Fig. 4 so that the leads 551 and 541 of the former are respectively opposite the leads 651 and 641 of the 45 latter.

Referring to Fig. 1, the customers' stations 52A to 52G are shown connected by lines 51A to 51G to a central telegraph station X. At the central station X, as is 50 shown by lines 24 and 25, each of the lines

51A to 51G is multiplied to the central station inward circuit or "concentration system" Y and to the central station outward circuit or "switching system" Z. More specifically, a group of customers' stations is 55 associated with a group of primary line finders 26, and a group of connectors 43; and the lines 51A, 51B, etc., connecting each customer's station in the group with the central station are multiplied to each primary 60 line finder in the associated group of such finders 26, and to each connector in the associated group of connectors 43. The number of primary line finders 26 and the number of connectors 43 to be provided depends 65 respectively upon the expected amount of busy hour inward and outward traffic, and this number may be varied as is found necessary to handle the traffic in an economical manner. As an example of a suitable arrangement, we may assume that each group of 200 customers' station lines is multiplied to a group of twenty primary line finders and each group of 100 lines is multiplied to a 70 group of 10 connectors.

75 The "concentration system" Y comprises a group of primary finders 26; a group of trunks 27 leading from the primary finders 26 to a group of selecting circuits 28, which provide access to trunks 29, 30, 31, 32 and 33, 80 etc.; groups of secondary line finders 34, 37, 40 associated with these trunks; and groups of printers 36, 39, 42, etc., associated by trunks 35, 38 and 41, etc. with the secondary finders. A selecting circuit is individual to 85 each primary finder. The groups of secondary finders 34, 37, 40, etc. each contain a plurality of secondary finders the number of which is determined, as in the case of the primary finders, by the amount of traffic to 90 the particular printer group 36, 39, 42, etc. Each trunk 29, 30, 31, 32 and 33 of the selecting circuits is multiplied to a different group of secondary finders 34, 37, 40, etc., so that whenever, for example, a customer dials to 95 select trunk 29, his line is invariably connected by means of an idle secondary finder in group 34 to the first idle printer in group 36. Each of the printer groups 36, 39, 42, etc. furnishes a particular class of telegraphic 100

service. For example, the printers in group 36 might be devoted to receiving land line telegrams, and those in group 39 to receiving messages for retransmission over a cable. 5 This invention contemplates that the following types of service will be available to the subscriber: (1) A connection to a telegraph recording operator for sending land line telegrams; (2) A connection to a cable recording 10 operator for sending cablegrams; (3) A connection to a chief equipment man; (4) A connection to an operating room traffic manager.

It will probably be found advantageous in practice to have one group of central station 15 operators handle inward calls and another group handle outward calls. The group of receiving operators may be further sub-divided so that each sub-group handles separate classes of inward calls; one group handling land line telegrams, another group cablegrams, etc.; and if so desired, separate sub-groups of sending operators may likewise handle separate classes of outward service. 20

The "switching system" Z includes groups 25 of connectors 43; groups of trunks 44; groups of second selectors 45 associated by the trunks 44 with the connector groups 43; trunks 46; groups of first selectors 47 associated by trunks 46 with the second selector groups 45; 30 trunks 48; and groups of printers 49 associated by these trunks 48, with the first selector group 47. The selector group 47 contains a plurality of first selectors, each individual to a central station sending operator's printer 35 in group 49. Each first selector is multiplied to the second selectors in selector group 45 in such a way that the first selector has access to sub-groups of second selectors, each capable of extending a connection to any one of 40 a particular group of 1000 customers' stations. The number of second selectors in any such sub-group is determined by the amount of traffic between the central station and the particular group of 1000 customers' lines to 45 which the sub-group of second selectors has access. Each second selector in a particular sub-group is multiplied to a particular sub-group of connectors, in connector group 43, in such a way that any second selector in a 50 sub-group has access to a sub-group of connectors each capable of extending a connection to any one of a particular group of 100 customers' stations.

A description of the operations which take 55 place in establishing the circuits in either direction between the central station and the subscriber's station will disclose the methods and means used in carrying out the invention as well as its novel features.

60 A general idea of the operation of the system may be obtained from a description of the incoming and outgoing operations respectively which take place when customer's station 52A, for example, desires to establish 65 connection with, say, a printer in printer

group 36 at the central station, and when the central station operator in charge of a printer in printer group 49 desires to establish connection, for example, with customer's station 52A. 70

The sequence of operations in establishing said inward circuit will be described first. On customer 52A operating a key to calling position, an idle primary line finder 26 at the central station finds his line 61A, connecting it to a selector switch in group 28, individual to the actuated primary line finder. When connected to the selecting switch, the customer then selects a type of service, as for example, that furnished by printer group 36 in the manner hereinafter described. After the customer has selected the type of service given by printer group 36 the first idle secondary line finder in the group of finders 34 selects the trunk 29 thereby connecting the calling station 52A to the first idle receiving operator's set in the printer group 36. Upon the establishment of connection between the calling subscriber's station and the called central station operator's set, the printer motor at the subscriber's station is alone started. As the central station operator's printer motor runs continuously, communication between the two stations can then be carried on. The release of the connection between the two stations at the end of a message is under the control of the central station operator, as will be described later, though the calling subscriber can stop his own printer motor. 80

The sequence of operations in establishing the outward circuit hereinbefore mentioned is as follows: when a central station operator in charge of a printer in printer group 49 desires to establish connection with customer's station 52A, he dials the number corresponding to that station. The first digit dialed causes the first selector 47, which is individual to his printer, to choose one of the trunks 46 leading to an idle second selector in the proper thousands group of the second selector groups 45. The second digit dialed operates the second selector, causing it to select one of the trunks 44 leading to an idle connector in the proper hundreds group of the connector groups 43. The third and fourth digits dialed operate the selected connector to establish a connection over lines 25 and line 51A to the called customer's station 52A. Assuming that the central station operator receives no indication that the called subscriber's line is busy, he then operates a key to "cut through" position, thereby starting the printer motor at the subscriber's station. As the central station operator's motor is running continuously, communication can then take place between the two stations. As in the case of the inward circuit, the release of the established connection is under the control of the central station operator, 90 95 100 105 110 115 120 125 130

though the called subscriber can stop his own printer motor.

Referring now to Figs. 2 and 3, which illustrate the outward circuit in detail, there is shown a calling operator's set 100; a first selector 200 which is individual to operator's set 100; a second selector 300 which is the first idle selector in the selected thousands group which has access to the customer's line; 10 a connector switch 400 which is the first idle connector in the selected hundreds group, a line relay 436 and a cut-off relay 438 which are individual to the called station and are common to both the inward and outward 15 circuits, and a subscriber's station 52A. It is apparent from the previous description of the system as a whole that the second selector 300 is multiplied by trunks 223, 224 and 251 to a number of first selectors similar to 200, which 20 likewise have access to it; the connector 400 is multiplied by trunks 323, 324 and 351 to a number of second selectors similar to 300, which also have access to it; and that the relay 438 is multiplied by wires 431 and 432 25 to a number of connectors similar to 400 which have access to relay 438 and the called customer's station, and conductors 441 and 442 are multiplied to the primary line finder banks in the group associated with the called 30 subscriber's station while 440 is connected to the group relay associated with the group of stations of which 52A is one.

As the customer's station is common to both the outward and inward circuits, to avoid 35 repetition it will be described first.

At the customer's station 52A a line circuit 51 extends from ground 50, through the sending contacts 52 of a printer, a line magnet 53, contact 55, a three position calling 40 key 54, lower winding 59 and upper winding 60 of a polar relay 58, and over line 51 to the central station. When contact 55 is closed, or when the calling key 54 is in its unoperated position, both the lower or high 45 resistance winding 59 and the upper or low resistance winding 60 of the polar relay 58 are in the line circuit. When the calling key 54 is operated to the right however, and contact 56 closed, the lower or high resistance winding 59 is shunted. The line circuit then extends from ground at 50, sending contacts of the printer 52, line relay 53, pulsing contacts 63 of the dial 64, contact 46, resistance 71 and lamp 70 in parallel, upper 50 winding 60 of polar relay 58, line 51 to the central station. The dial lamp 70, whose operation will be described later, is shunted by resistance 71, which is of such a value that the dial lamp will not be lighted until the 55 circuit is ready for the operation of the subscriber's dial 64. The dial 64 is of usual type, with pulsing contacts 63 and off-normal contacts 65. The polar relay 58 has a tongue which, in the normal idle condition 60 of the circuit is held away from its back

contact A by a small current through both windings 59 and 60 in series, or through winding 60 alone. Upon a reversal of current through the polar relay 58, however, this tongue closes against its back contact A and 70 is held there by a biasing spring 66. Another reversal of current through the polar relay will restore the polar relay tongue to normal and open contact A. The relay tongue controls a circuit for operating a control relay 67, which in its preferred form is capable of operating upon direct or alternating current. When the polar relay tongue is in its normal position away from contact A, the control relay 67 is deenergized, 75 but when the tongue moves against contact A, the control relay is energized over a circuit extending from source of current 74, resistance 68, contact A of polar relay 58, contact A of "release" relay 72, off-normal contacts 65 of the dial 64, winding of control relay 67, resistance 69 to source of current 74. The control relay 67 has two contacts A and B. Contact A when closed, completes the circuit of printer motor 73, while contact 80 B when closed, and when the calling key 54 is against contact 55, removes the dial lamp 70 from the line circuit.

The release relay 72, which is adapted when operated to deenergize the control relay 67 and open the shunt around the high resistance 59 of polar relay 58, is controlled both by the key 54 when operated to the clearout position so that contact 61 is momentarily closed, and by the tongue of polar relay 58. When the polar relay tongue is against its back contact A and the control relay 67 is operated, the momentary closing of contact 61 by the calling key 54 establishes a circuit for operating the release relay 72 from source of current 74, resistance 68, contact A of polar relay 58, contact 61 of key 54, winding of release relay 72, resistance 69, back to source of power 74. In operating, the release relay locks itself over 105 an obvious circuit through contact 62 of key 54. The operation of the release relay 72 deenergizes the control relay 67, which in turn opens the motor circuit and removes the short circuit from the high resistance 110 winding 59 of polar relay 58, reducing the line current. The release relay 72 is deenergized by the retraction of key 54 which closes contact 56. This opens contact 62 breaking the locking circuit of the release relay. If 115 the release relay is operated by the subscriber before the central station operator desired to disconnect, the operation by the latter of a recall key in the case of a receiving operator, or the operation of a key to 120 dial position in the case of a sending operator, to be described later, reconnects negative battery to the line circuit opening contact A of polar relay 58, thus deenergizing the release relay 72. Upon restoration of the re- 125

call key or the operation of a key to "cut through" position by the central station operator, positive current is reconnected to the line circuit, and the subscriber's printer motor 73 is started as described above.

- To initiate a call the customer operates the calling key 54 to the calling position, closing contact 56; thereby short-circuiting the high resistance winding 59 of the polar relay 58.
- 10 The line circuit now extends through the upper winding 60 of the polar relay 58, the dial lamp 70 which is shunted by resistance 71 and is not lighted by the line current even though thus increased, contact 56 and operating spring of the calling key 54, the pulsing contacts 63 of the dial 64, the printer line magnet 53, sending contacts 52 to ground at 50. The short-circuiting of the high resistance winding 59 increases the line current with the
- 15 result that the line relay 436 at the central telegraph station is operated. The operation of line relay 436 starts an idle primary line finder 26 (Fig. 1) of the group associated with the calling line, to connect customer's station to a selecting circuit 28 (Fig. 1). The further operation of the circuit for handling inward calls will be described in more detail later.

- It will suffice for the present to observe that
- 30 after a connection is finally established between the calling customer's station and a central office receiving printer, such as printer 36, 39, 42, etc., positive potential is applied to the line. This results in the operation of
- 35 the polar relay 58 of the customer's station in a direction to close its contact A which energizes the control relay 67. The control relay closes its contact A and starts the printer motor 73. It also closes its contact B and establishes a shunt around the dial lamp 70 which having been lighted when the customer's line was extended to the selecting circuit is now extinguished. Calling key 54 should preferably be restored to its original
- 45 unoperated position against contact 55 at this time. The line circuit may now be traced from ground at 50 through printer sending contacts 52, line magnet 53, contact 55 of calling key 54, contact B of control relay 67, upper winding 60 of polar relay 58, line 51 to the central telegraph station and through the "concentration system A" (Fig. 1), at that station to a receiving operator's set 36, 39, 42, etc. As will be described in more detail later,
- 55 the printer motor associated with each receiving operator's set at the central station is continuously running while the receiving operator is in attendance. Consequently it is unnecessary, and no means are provided,
- 60 for starting his printer motor.

When the desired messages have been transmitted, the central station operator releases the established connection, as will be described later. This indirectly removes the

65 line circuit 51 from battery 433 associated with line relay 436. The change in the direction of the current passing through the polar relay 58 causes contact A of polar relay 58 to open. This releases control relay 67 which 70 stops the motor 73 and restores the customer's station circuit to normal. Should the calling subscriber operate the calling key 54 to the release position, thereby closing contact 61 before the central station operator desires to 75 release the connection, the latter may operate a recall key, which deenergizes the release relay 72, and then restart the subscriber's motor 73 as described above.

To initiate an outgoing call from the central station, the sending operator dials the number assigned to the customer's station line, operating the proper selector switches in groups 47 and 45 (Fig. 1), and the proper connector switch in group 43 in a way 80 that will be explained in more detail later. The result of the operation of these intermediate switches is that the central station operator establishes a direct connection to the customer's station. After this connection is established, by operating a key the central station operator applies positive potential to the line from the battery 101 (Fig. 3). As in the case of the inward circuit previously described, this positive current causes the polar 85 relay 58 to close its contact A thereby operating the control relay 67. The control relay by closing its A contact starts the motor 73 and by closing its B contact shunts out the high resistance winding 59 of the polar relay 58. As the calling key 54 is in its normal position, the station line circuit for outward service is now the same as for inward service after the customer has released the calling key and has established connection 100 with the printer at the central station.

The breaking of the established connection by the central station operator is followed by the same effects at the customer's station in this case as in the case of the inward circuit. In this case also the central station operator can deenergize the released relay 72 at the subscriber's station, if it is operated before the former desires to disconnect.

Referring now to Fig. 3, central station sending operator's set 100 comprises apparatus for dialing, for transmitting and receiving printer signals, and a three position circuit-controlling key. A printer motor, not shown, is also located at this set and is 115 left running continuously while the sending operator is in attendance. This key 121 is adapted to be moved into three positions, namely, to "release", "dial" and "cut-through" positions. Normally it is in release position, at which time contacts 128 and 129 are closed; while contact 130 is open, so that the dial lead 123 to the selector 200 is open. The line circuit of the sending operator's set now extends from positive battery 101, 130

- through resistance 102, sending contacts 103 of a printer, relay 104, resistance 131, contact 129 to ground at 132. The operator's printer set line circuit is thus held closed.
- 5 The differentially wound line relay 104 has an upper winding 105 and a lower winding 107. One end of the lower winding is grounded at 106, while its other end is extended through resistance 108 to the positive pole of grounded battery 101. The current through this lower winding is normally about half that through the upper winding. The line magnet 113 of the printer is in a local circuit extending from ground 114 through 15 winding of line magnet 113, contact A of relay 104 which is normally closed, resistance 109; or when contact A is open, through condenser 115 and resistances 116 and 109, to the positive pole of battery 101. When 20 printer signals pass through the winding 105 of line relay 104, the circuit from battery 101, winding 107 of relay 104 to ground at 106, cooperates with the line circuit causing contact A of relay 104 to open and close, thus 25 operating printer magnet 113. The line circuit for the selector switch, which is normally open, extends from grounded negative battery 133, resistance 134, contact 128, to an open contact F of relay 201 of the first 30 selector 200.
- When the key 121 is operated to "dial" position closing contact 130, the dial lead 123 is closed, thereby establishing a circuit for operating relay 205 of first selector 200, from 35 ground 132, through contact 130, dial 127, resistance 135 and busy lamp 126 in parallel contact A of relay 201, windings 208 and 207 of relay 205 in series, to grounded battery 206. Relay 205 thereupon energizes, 40 closing its A contact. An operating circuit for slow releasing relay 210 is thereby completed from grounded battery 209 winding of relay 210, the A contact of relay 205, the E contact of relay 201 to ground at 202. The 45 operation of relay 210 closes its A contact, thereby placing ground at 211 on release lead 224.
- The sending operator now dials the first digit of the calling signal allotted to the 50 desired customer's station. In response to the impulses corresponding to this first digit, relay 205 is energized and deenergized so that it alternately closes its A and B contacts.
- When relay 205 opens its A contact the 55 slow releasing relay 210 is not deenergized, but remains energized throughout the entire series of impulses. When relay 205 closes its B contact, relay 212 and vertical magnet 213 are operated. Since relay 212 is slow releasing, it likewise remains energized, during the entire series of impulses. The vertical magnet 213, on the contrary, responds to the dialed impulses. The operating circuit for 60 vertical magnet 213 and relay 212 may be traced from grounded battery 214 through the winding of vertical magnet 213, winding of relay 212, contact B of relay 210, contact B of relay 205, contact E of relay 201 to ground at 202. The operation of the vertical magnet steps the wiper shaft (not shown) up to the bank level corresponding to the dialed digit. At the first upward movement of the wiper shaft the off-normal contacts 219 and 220 close.
- Upon the operation of relay 212 and the off-normal contacts 219 and 220, relay 216 is energized over a circuit from grounded battery 215, winding of relay 216, off-normal contact 219, contact A of relay 212, contact A of relay 210 to ground at 211. Relay 216 locks itself over a circuit from off-normal contacts 219, through contact A of rotary magnet 217, contact B of relay 216 and contact E of relay 201 to ground at 202.
- The wipers 225, 227 and 229 have now been stepped up to the level of the bank terminals 226, 228, 230, etc. having access to the group of 1000 lines which includes the called line. Although only the above positioned bank terminals are shown leading to the first idle second selector 300, other bank terminals (not shown) but connected by trunk conductors similar to 223, 224 and 251 to other second selectors, are capable of being tested by test wiper 225. When some of the trunks are busy, the bank terminals corresponding to terminal 226 having access to the busy trunks will be grounded at a second selector 300 if the second selector has not yet found a connector, or at a connector such as 400 when the selector is fully operated, in a way which will be described later, while those having access to the idle trunks will be ungrounded.
- At the end of the series of impulses corresponding to the first digit dialed, relay 205 remains energized with its contact A closed. Relay 210 also remains energized, grounding the release lead 224 at 211. Relay 212 however, releases as its circuit is opened at contact B of relay 205. Upon the release of relay 212, an operating circuit is closed for rotary magnet 217 from grounded battery 218, through winding of rotary magnet 217, contact A of relay 216, (relay 216 having been operated upon closing of off-normal contacts), contact B of relay 212 and contact A of relay 210 to ground at 211. The rotary magnet operates and rotates the wipers 225, 227 and 229 so that each wiper now contacts with the first corresponding bank terminal of the selected level. The rotary magnet at its A contact also opens the locking circuit previously traced for relay 216. As the original operating circuit of relay 216 is now open at contact A of relay 212 as a result of the release of that relay, relay 216 will now release, opening its contact A and thereby causing the release of the rotary magnet 217. When the rotary magnet 217 releases and the wiper 225

is connected to an idle bank terminal 226, a circuit may be traced from grounded battery 215 through winding of relay 216, off-normal contact 219, contact A of rotary magnet 217, winding of relay 201, contact 203, release lead 224, contact A of release relay 210 to ground at 211. When the rotary magnet releases and the wiper 225 is connected to a busy bank terminal 226, a circuit may be traced from grounded battery 215, through winding of relay 216, off-normal contact 219, contact A of rotary magnet 217, contact C of relay 201, conductor 224, wiper 225 to ground on terminal 226 which is connected to the 15 grounded release lead of a second selector or a connector.

From the circuits traced it is seen that when the bank terminal 226, connected to wiper 225, is busy and grounded, the operating circuit for relay 216 is grounded at bank terminal 226 without passing through relay 201. Relay 201 consequently remains unoperated. The operation of relay 216 closes a circuit for operating the rotary magnet 217. The rotary magnet 217 then operates, rotating the wipers one step and opening at its contact A the operating and locking circuits for relay 216. This interaction between relay 216 and the rotary magnet 217 continues in this manner until the rotating wiper reaches an idle trunk.

When this occurs, as described above, relay 201 is connected in series with relay 216. Relay 216 is marginal and does not operate in series with relay 201, the winding of which is of comparatively high resistance. The failure of relay 216 to operate when the wiper 225 is rotated to an idle trunk leaves the rotary magnet circuit open at contact A of relay 216, preventing further rotation of the wiper 225 on that level.

Upon operating, relay 201 connects test bank contact 226 to ground at 211 over a circuit from test bank contact 226, wiper 225, 45 contact D of relay 201, release lead 224 contact A of relay 210 to ground at 211. This makes the trunk busy and prevents other first selectors from establishing a connection with the same trunk.

50 A digression is now necessary to explain that the second selector 300 and the first selector 200 are identical, and the details of selector 300 have therefore been omitted from the drawings. In describing the operation of selector 300, identical elements of the two selectors except those numbered in the drawings will be referred to by the same numeral, but the elements of selector 300 will be distinguished from those of selector 200 by the addition of the letter A to the numeral.

To return to the sequence of operation, relay 201 connects the line conductors 151 and 251 and extends the latter to open contact F of relay 201A at the second selec-

tor; the dial lead 223 to battery 206A through both windings 208A and 207A of relay 205A; and the release lead 224 to open contact A of relay 210A.

The first selector 200 is multiplied by 70 means of conductors 223, 251 and 224 to the bank contacts of first selectors (not shown), but as lead 224 is now grounded and therefore bank contacts 226 of these other first selectors are also grounded, none of these first selectors can become connected to the particular second selector, in this case selector 300, that is now connected to the selector 200 upon the operation of relay 201.

The release lead 224 is connected to release lead 224A of the second selector, which

as yet is not grounded at 211A. As the dial lead now extends from battery 206A through windings 207A and 208A of relay 205A of the second selector, contact A of relay 201A, 85 bank contact 228 and wiper 227 of the first selector, conductor 223, contact B of relay 201, lead 123, resistance 135 and lamp 126 in parallel, dial 127 and contact 130 of calling key 121 to ground at 132, the circuit for relay 205A of the second selector is completed and it is accordingly energized. When this relay is energized, a circuit for operating relay 210A of the second selector is completed. The operation of relay 210A ap-

plies ground at 211A of the second selector to release lead 224A. The release lead now extends back from ground at 211A of the second selector through conductor 224A, test bank contacts 226, wiper 225, conductor 224, contact D of relay 201, contacts 203, winding of relay 201, contact A of rotary magnet 217, off-normal contact 219 and winding of relay 216 to grounded battery 215. Relay 210 of the first selector is released by the operation of relay 201 since its operating circuit is open at contact E of that relay. The operation of relay 201 also by opening its A contact opens the operating circuit for relay 205 which also releases. As relay 210 of the first selector is of the slow releasing type, however, it does not release until relay 210A of the second selector is operated, grounding the release leads 224 at 211A of the second selector. Relay 201 of the first selector is, therefore, held operated over the circuit previously traced, extending from ground at 211A. Relay 201 of the first selector by opening its E contact also prevents the operation of release magnet 221 when relays 205 and 210 of the first selector are released.

When all the trunks on the selected level are busy the first selector will rotate beyond the last or tenth contact. The eleventh rotary operation of the switch opens contact 203 and closes contact 204 which respectively open the circuit of relay 201 and short circuit the upper or high resistance winding 208 of relay 205. The current in the dial lead

115

120

125

130

123 is accordingly increased and a busy lamp 126 at the central station operator's set is lighted. Upon observing this indication of a busy trunk, the operator moves the calling 5 key 121 to "release" position removing ground at 132 from relay 205. Relay 205 is thereby released and in turn releases relay 210. The release of both of these relays closes an operating circuit for the release magnet 10 221 as relay 201 is unoperated, and this magnet returns the selector to normal. The operating circuit for this magnet may be traced from grounded battery 222, winding of release magnet 221, off-normal contact 220, contact 15 C of relay 210, contact B of relay 205, contact E of relay 201 to ground at 202.

When the outward circuit has been extended to the second selector 300, the second or hundreds digit dialed by the sending operator 20 operates this selector in the same way that the first selector was operated by the first digit dialed. The operation of this second selector 300 extends the outward circuit over conductors 351, 323 and 324 to the first 25 idle connector switch 400 (see Fig. 2) associated with the group of 100 lines containing the called customer's station.

If all the trunks on the selected level of the second selector are busy, the previously 30 described operations will result, the busy lamp 126 will be lighted and the sending operator informed that a busy trunk condition exists. The operator can then move key 121 to "release" position, as described above, 35 restoring both the first and the second selectors to normal.

If there is an idle trunk on the selected level the printing line will be extended by the operation of relay 201A through the first 40 and second selectors to open contact D of relay 421 of the connector switch 400. The dial lead will be extended through the first and second selectors to the connector switch 400 and through both windings 402 and 403 45 of relay 401 in series to grounded battery 404. As the dial circuit is complete from battery 404 associated with relay 401 to ground 132 at the central station, relay 401 will operate. The operation of relay 401 energizes 50 relay 406 which is slow releasing. The circuit for operating relay 406 extends from grounded battery 407 through winding of relay 406, contact A of relay 401 to ground 55 405. Relay 406 on closing its contact B applies ground at 408 to the release lead 424 which extends back from the connector switch to hold operated relay 201 of the first and relay 201A of the second selector switches. As in the case of relay 210 of selector 60 200, relay 210A of selector 300 is not released until relay 406 of the connector applies ground at 408 to release trunk 424.

The connector switch 400 is now operated by the third or tens digit dialed by the sending operator. Relay 401 alternately closes

its A and B contacts in response to the impulses corresponding to this digit in the same manner as did relays 205 and 205A of the two selectors. Relay 406 being slow releasing remains energized with its contacts closed throughout the entire series of impulses corresponding to this digit. When contact B of relay 401 is closed, a circuit is established for operating the slow release relay 412 and the vertical magnet 413 in series. This circuit 70 may be traced from grounded battery 414, winding of vertical magnet 413, winding of relay 412, off-normal contact 410, contact C of relay 406, contact B of relay 401 to ground at 405. As relay 412 is slow releasing, it 80 likewise remains energized throughout the entire series of impulses. The vertical magnet 413 on the other hand operates in response to the impulses and steps the wipers 427 and 429 up to the level corresponding to the 85 dialed digit.

The first vertical movement of the wiper shaft (not shown) releases the off-normal contacts closing contacts 409 and 411 and opening contact 410. The closing of these contacts has two results. First, it prepares a circuit for the release magnet 426, though this magnet cannot operate until relays 401 and 406 are deenergized. Secondly, it changes the pulsing circuit through the vertical magnet 413. This circuit now extends from ground 405, contact B of relay 401, contact C of relay 406, contact 411, contact A of relay 412, winding of relay 412, winding of relay 413 to grounded battery 414. 100

At the end of this group of impulses corresponding to the tens digit, relay 401 comes to rest energized, with its A contact closed. Relay 406 is thus held energized while relay 412 whose circuit is open at contact B of 105 relay 401 is released.

The units digit is then dialed by the sending operator causing relay 401 to energize and deenergize. Since the pulsing circuit is now changed, this closes parallel operating 110 circuits for the rotary magnet 424 and the relay 417. Relay 417 operates at the first impulse and, as it is slow releasing, remains energized throughout the series of impulses. The rotary magnet 424, on the contrary, operates in response to each impulse and steps the wipers 427 and 429 around to the terminals of the called line. The operating circuit for the rotary magnet may be traced from grounded battery 423, winding of rotary magnet 424, contact E of relay 421, contact D of relay 416, contact B of relay 412, off-normal contact 411, contact C of relay 406, contact B of relay 401 to ground at 405. 120

The circuit for operating relay 417 may be 125 traced from grounded battery 418, winding of relay 417, contact D of relay 416, contact B of relay 412, off-normal contact 411, contact C of relay 406, contact B of relay 401 to ground at 405. The operation of relay 417, 130

by closing its D contact, establishes a shunt path around the D contact of relay 416 to prevent the interruption of the pulsing circuit in case that relay should operate momentarily when the wipers 427, before reaching the called line, pass over the terminals of a busy line. Relay 416 may possibly operate under these conditions, because wiper 427 is grounded when it comes in contact with the 10 bank contact of a busy station line and an operating circuit might thereby be established for relay 416. This possible operating circuit may be traced from grounded battery 415, winding of relay 416, contact A of relay 421, contact B of relay 417, wiper 427 to the grounded bank terminal 428. If relay 416 should operate in such a case, the shunt path previously mentioned prevents its operation from opening the pulsing circuit at its D 20 contact.

If the called line is busy, the test bank contact 428 now connected with wiper 427 will be grounded through the wiper of some other connector or line finder switch. In this case 25 relay 416 will operate. Relay 417, being of the slow releasing type, remains energized for a short period after the wipers 427 and 429 reach the terminals of the called line. But since the circuit for relay 417 is open at 30 contact B of relay 401, due to the closing of the pulsing contact 125 of the dial 127, it releases shortly afterwards. If relay 416 operates during this interval, that is, while the wiper 427 is in contact with terminal 428 of 35 the called line and relay 417 is operated, relay 416 will be locked when relay 417 releases. The locking circuit for relay 416 in this case may be traced from battery 415, winding of relay 416, contact A of relay 421, 40 contact C of relay 417, (relay 417 now being released) contact B of relay 416, conductor 424, contact B of relay 406 to ground 408. Relay 416 at its D contact opens the pulsing circuit so that any further operation of the 45 sending operator's dial can have no effect on the connector switch. Relay 416 at its C contact also opens the circuit of the lower operating winding 422 of relay 421 so that the relay cannot operate.

The operation of relay 416 likewise establishes a shunt around the upper or high resistance winding 402 of relay 401, thus increasing the current on the dial lead 323 which extends to ground 132 at the sending 50 operator's calling key 121, and lighting the operator's busy lamp 126. This circuit may be traced from grounded battery 404, winding 403 of relay 401, contact A of relay 416, contact E of relay 417, dial lead 423 through the first and second selectors, busy lamp 126, contact 130 to ground at 132.

Upon this indication of a busy customer's line the operator moves the calling key 121 to "release" position, removing ground from dial lead 423 and releasing relay 401 which

in turn releases relay 406. The release of relays 406 and 401 closes the previously prepared circuit for the release magnet 426 of the connector switch and this magnet restores the connector to normal. The operating circuit for the release magnet may be traced from grounded battery 425, through winding of magnet 426, contact F of relay 421, off-normal contact 409, contact D of relay 406, contact B of relay 401, to ground at 75 405. The release of relay 406 also removes ground at 408 from release trunk 424, thus opening the operating circuit of relay 201 of the first selector, relay 201A of the second selector, and relay 416. The release of relay 201 of selector 200, by closing its E contact, results in the operation of the release magnet 221 which restores selector 200 to normal. In a similar manner the release of relay 201A causes selector 300 to restore to normal. 85

If the called station is not busy, test bank contact 428 will not be grounded but will be connected to battery 437 through cut-off relay 438. In this case relay 416 does not operate, since the batteries associated with relays 416 and 438 are of the same polarity and potential. Relay 421, however, does operate. The sequence of operations of the connector switch when the called line is busy, and when it is not busy, are the same up to the point when the wipers 427 and 429 have connected with the called line. Beyond this point the operations of the connector are different in each case. When the called station is not busy, relay 417 releases at the end of the 95 series of units digit impulses since its circuit is opened at contact B of relay 401. When relay 417 releases a circuit is closed for operating relay 421. This circuit may be traced from battery 437 associated with cut-off relay 438 through the test bank terminal 428, wiper 427, contact A of relay 417, winding 422 of relay 421, contact C of relay 416, release trunk 424, contact B of relay 406 to ground at 408. Relay 421 operates to close its locking contact C first, locking the relay through contact A of relay 406 to ground at 408. Contact B of relay 421 then operates connecting ground at 419 directly through 100 wiper 427 to the test bank contacts 428, making this trunk busy and operating cut-off relay 438. At its contacts E and A relay 421 also opens the rotary magnet circuit and the operating circuit for relay 416 respectively 105 so that further operations of the operator's dial will not interfere with the established connection to the called line. If the circuit for relay 416 were not open, relay 417 would operate in response to dialed impulses to close 110 its B contact and thereby establish a circuit for relay 416 through contact B of relay 421 to ground 419. Relay 421, by closing its D contact also extends the line circuit 451, through wiper 429, bank terminal 430, con- 115 120 125 130

tact B of relay 438, to ground 50 at the called customer's station.

When the customer's line has been selected in the manner above described, the central station operator moves the key 121 to the "cut-through" position opening contact 128 to remove negative battery 133 from the line circuit and closing contact 136 to connect the central station printer set and positive battery 101 to the line. The contact 137 is also closed so that the dial is always shunted when the key 121 is in its "cut-through" position. As a result of this current reversal over the line circuit, the polar relay 58 at the customer's station closes its A contact. The closing of this contact energizes the control relay 67, which closes its A and B contacts. The closing of the former starts the station printer motor 73. The closing of the latter shunts the winding 59 of the polar relay 58.

The line circuit may be traced from ground at 50, the sending contacts 52 of the printer, line magnet 53, contact 55 of calling key 54, contact B of control relay 67, winding 60 of relay 58, line 51, contact B of cut-off relay 438, connector 400, selector 300, selector 200, line 151, to battery 101.

As the printer motor at the central station set is running continuously and the customer's printer motor has been started, the sending operator may now send to the customer's station. When the message has been transmitted and acknowledged the sending operator restores calling key 121 to "release" position removing ground from dial lead 123; thus opening the operating circuit for relay 401. Relay 406 is released when relay 401 releases, removing ground from the locking circuit of relay 421 and from the release lead 424. The removal of ground from the release lead 424 opens the operating circuits of relay 421, relay 201 of selector 200, and relay 201A of selector 300. The release of the relays 201A and 201 closes an operating circuit for the release magnets 221 and 221A of both of these selectors, and the release magnets restore the selectors to normal. The circuit of the release magnet of the connector switch extends through contact F of relay 421. This arrangement of the release circuit prevents the release magnet from restoring the connector to normal until after relay 421 has been released, so that the wipers of the connector switch will be open circuited when they restore and thus avoid any possible interference with other lines on the same level when traversing the bank terminals of such lines while restoring to normal. When relay 421 releases, however, the connector switch restores to normal. The release of relay 421 also removes ground at 419 from the test bank terminal 428, so that the cut-off relay 438 releases and applies negative potential from battery 433, resistance 434 winding of

line relay 436 and contact C of cut-off relay 438 to station line 51, opening contact A of polar relay 58 which releases control relay 67 stopping the motor and restoring the station to normal as previously described.

As an alternative method of stopping the customer's printer motor, the customer may operate the key 54 to the "release" position, thereby closing contact 61. The release relay 72 is thus operated over a circuit previously described, and locks itself over an obvious circuit through contact 62 of key 54. The energization of the release relay opens the circuit of the control relay 67 at contact A of the release relay, thus stopping the subscriber's motor 73. In this case, however, the connector and selector switches are not released, but the line current is reduced by the opening of the shunt around the lower high resistance winding of the polar relay 58. This reduced line current makes the central station printer spin without printing, thus informing the sending operator that the customer's printer motor has been stopped. The sending operator may now release the connection as previously described or if desired may start the customer's motor again by momentarily operating the key 121 to "dial" position, and then restoring it to the "cut-through" position. When in the "dial" position, the key connects negative battery to the line circuit, which opens contact A of polar relay 58 thus opening the circuit of the release relay 72 and releasing it. Upon moving the key 121 back to "cut-through" position, the central station operator reconnects positive battery 101 to the line circuit, closing contact A of polar relay 58 and restarting the customer's printer motor in the manner described above.

The complete circuit for inward service is shown by connecting the customer's station, comprising the parts shown in Fig. 2, to line 51 leading to contact C of the cut-off relay 438 and the line relay 436 shown in Fig. 4 and by placing line 551 and line 541 of the primary finder 500 end to end with line 651 and line 641 respectively of the selector circuit as shown in Fig. 5.

Referring to Fig. 4, the line and "cut-off" relays 436 and 438 are individual to each customer's line and are used both in the inward circuit and the outward circuit as previously described. The line 51 extending from the customer's station is multiplied after passing through these relays to associated groups of connectors and primary line finders through multiple bank contacts 428 and 430, and multiple bank contacts 543 and 547, respectively. The bank terminals 543 and 547, connected to the calling customer's line 51, and the bank terminals 545 and 549 connected to another customer's station are alone shown in the finder switch 500. It is obvious, however, from the general description of the

70

75

80

85

105

110

115

120

125

130

system previously given, that 198 other customers' stations are connected to finder switch 500 and that the 200 customers' stations connected to the switch are multiplied 5 by means of conductors such as 550 and 552 to a plurality of other finder switches, the number of which is determined by traffic conditions.

The line finder switch 500 is in general 10 similar in mechanical construction to the selector and connector switches used for outward service. Each switch, however, has two hundred point banks having ten levels and twenty terminals per level instead of the 15 one hundred point bank terminals possessed by the connector switches. The lower bank carries the line wire terminals 547, 549, etc. for two hundred lines while the upper bank carries the private or test terminals 543 and 20 545 for the same two hundred lines. Unlike the connector and selector switches, the primary line finder hunts both in the vertical and rotary directions and also operates automatically instead of in response to dial 25 impulses as do the connector and selector switches.

When the customer operates a key 54 (see Fig. 2) to "calling" position to initiate a call, the high resistance winding 59 of polar 30 relay 58 at the customer's station is shunted in the manner previously described, and an increased line current results which operates line relay 436 at the central office. This relay closes a circuit to connect the battery 437 associated with relay 438 to the test bank 35 terminal 543. It also operates group relay 554. The circuit for placing battery on the test bank terminal 543 may be traced from battery 437, winding of relay 438, contact B 40 of relay 436, conductor 442 to test bank terminal 543. The circuit for energizing the group relay 554 may be traced from grounded 45 battery 555, winding of relay 554, contact A of relay 436 to ground at 535. Ten of these relays 554 are provided for each group of two hundred lines or one relay for each twenty lines on the same level. The relay 554 grounds the proper vertical commutator terminal of each line finder switch, that is, it 50 grounds the first contact 508 on the "home switch" and also, for use in case the "home" switch is busy, grounds successive contacts 509, etc. on successive switches.

The "home switch" is a device for reducing 55 the "hunting" time of the vertical commutators. As there are ten levels of bank terminal in each primary line finder, if a particular line were invariably associated in each of the finders with the tenth level of bank 60 terminals, it is plain it would always be necessary to step the vertical commutator of any finder ten levels upward in order to find that line. To obviate the necessity of stepping the commutator up in this way, a "slip" is introduced 65 into the bank multiple, that is, each

group of twenty lines terminates on different levels in each of the primary finders in a particular group. For example, if there are twenty line finder switches for a group of 200 lines, each sub-group of twenty lines terminates on lowest level of two switches; the second level of the next adjacent two switches and the third level of the third pair of switches, etc., being one level higher on each successive pair of switches. A switch, on 70 which a sub-group of twenty lines appears in the first level, is known as the "home" or "first preference" switch for that group. The relays 554 are arranged so that each line will normally start a "home switch" but if that switch is busy it will start the second "home switch", and if both are busy it will start a switch in which the lines containing the calling line are on the second terminal bank level or if these are busy it will start a switch having the calling lines on the third level, etc. As 75 a result of this arrangement, the switches are usually required to step up only one level and it is only when most of the switches are busy 80 that they are required to step up to the higher 85 levels. It is apparent that the contacts 508, 509, etc., of the vertical commutators must be wired with a multiple slip in a manner similar to contacts 543 and 547 which are shown multiplied by leads 550 and 552 respectively to other primary finder switches. 90

The circuits which cause the initial energization of the "home switch" and then of successive switches if the "home switch" is 95 busy, will be described later.

Relay 554 at its A contact also grounds the start lead 553 to energize relay 512 of the "home switch" or, if that switch is busy, of the first idle switch following. The circuit for relay 512 may be traced from grounded 100 battery 513 through winding of relay 512, contact E of relay 536A, start lead 553A, contact A of relay 554, contact A of relay 558 which is normally energized to ground 562. 105

Relay 512 operates stepping relay 525. The circuit for 525 may be traced from grounded 110 battery 540, contact H of relay 536A, winding 563 of relay 525, contact A of rotary magnet 523, contact A of vertical magnet 522, contact A of relay 512 to ground 514. Relay 525 closes a circuit for operating the vertical magnet 522 from grounded battery 540, through contact H of relay 536A, winding of the vertical 115 magnet 522, contact F of slow-operating relay 515, contact A of relay 525, contact A of relay 512 to ground at 514. Upon the completion of this circuit, the vertical magnet 522 operates, raising the switch shaft (not shown) including commutator wiper 507. The movement of this shaft closes the vertical "off-normal" contact 530 and opens contact 529. The release magnet 527 does not operate at this time as its circuit is open at contact D of relay 512. The vertical commutator segments 508, 509, etc., are open except the top 120

130

segment 510 which is permanently grounded at 511 and the segment corresponding to the level of the calling line which is grounded at 556 through contact B of relay 554. The 5 tenth or top segment 510 is permanently grounded so that the vertical commutator will invariably stop on the tenth level, should the start lead 553A be accidentally grounded. Relay 525 and vertical magnet 522 are so arranged 10 that they will mutually operate and release one another so long as the wiper 507 is not in contact with a segment which is grounded at 556. In other words, the vertical commutator shaft will be stepped vertically 15 until it reaches the level in which the calling line appears or until it reaches the tenth level. The operation of vertical magnet 522 opens its A contact and the original operating circuit for relay 525. If the vertical commutator segment 508, 509, etc., which is then in contact with the brush 507, is not grounded at 556, relay 525 will release. The release of relay 525, releases the vertical magnet 522 as its circuit is then opened at contact A of relay 525. The release of vertical magnet 522 closes its A contact which in turn causes the 20 operation of relay 525. Relay 525 then closes A contact and operates vertical magnet 522 again, causing the switch to take a 25 second vertical step.

The mutual interaction between relay 525 and vertical magnet 522 continues until the brush 507 reaches the grounded commutator segment 508, 509, etc., which is on the 30 first level in the "home switch" and on higher levels for other switches. When this occurs, relay 515 operates in series with the right hand winding 563 of relay 525. This operating circuit may be traced from battery 540, through contact H of relay 536A, winding 563 of relay 525, contact A of rotary magnet 523, winding 517 of relay 515, brush 507, vertical commutator segment, 35 contact B of relay 554 to ground at 556. The closing of this circuit holds relay 525 energized and prevents any further opening of the vertical magnet circuit at contact A of the former relay, thus preventing further vertical stepping of the brush 507. Relay 515 locks itself through its upper winding 516 in series with the winding of the vertical magnet 522, from battery 540, contact H of relay 536A, vertical magnet 522, upper winding 516 of relay 515, contact D of relay 515, contact A of relay 512 to ground 514. The 40 resistance of the winding 516 of relay 515 which is now in series with the vertical magnet 522 is such that the current from battery 540 is now insufficient to operate vertical magnet 522 and it releases. Relay 515 also prepares a locking circuit for relay 501, transferring that circuit from a circuit extending from ground 531 at the "off-normal" contacts, contact C of relay 515, contact E of relay 501 to grounded battery 504, to a

circuit which is grounded by each operation of the rotary magnet. This prepared circuit will be traced later.

The operation of relay 515 in opening its A contact also opens the release magnet circuit. This circuit when closed may be traced from grounded battery 528, winding of release magnet 527, "off-normal" contact 530, contact A of relay 515, contact B of relay 532, contact D of relay 512 to ground 531 at the "off-normal" contacts. It is apparent from this circuit that the release magnet can operate only when relays 515, 532 and 512 are released.

The operation of relay 515 transfers the stepping circuit from vertical magnet 522 to the rotary magnet 523. The operating circuit for the magnet may be traced from grounded battery 524, winding of rotary magnet 523, contact E of relay 515, contact A of relay 525, contact A of relay 512 to ground at 514. Relay 515 is designed to be slow in operating in order to allow a short time between the last vertical step of the commutator shaft and the first rotary step 90 of wipers 542, 544, 546 and 548 in order to prevent possible snagging of these wipers which might result from their vertical vibration.

The operation of the rotary magnet 523 over the circuit previously traced opens its contact A and the operating circuit for relay 525, and relay 525 is released. The rotary magnet circuit is in turn opened at contact A of relay 525 and accordingly releases. 100 This interaction between relay 525 and the rotary magnet 523 continues, stepping the wipers around until one of the test wipers 542 or 544, reaches the bank terminal of the calling line. This calling line is connected to battery 437 through winding of "cut-off" relay 438 as has been previously described. 105

It will be understood that during the rotary stepping of the switch, locking circuits of relays 501 and 532 are opened each time 110 the rotary magnet releases opening its B contact. This is for the purpose of preventing false operation of these relays when the wipers step over terminals of busy lines, the test contacts of which are grounded. In such cases a circuit is closed from ground to the bank terminal 545, through wiper 544, upper winding 502 of relay 501, contact D of relay 532, contact D of relay 501, left hand winding 526 of relay 525, contact A of relay 512 to ground at 514 or from ground at bank terminals 543 through wiper 542, upper winding 533 of relay 532, contact B of relay 536A, left hand winding 526 of relay 525, contact A of relay 512 to ground at 514. 115 120 125

When the circuit through the right hand winding 563 of relay 525 is opened at contact A of the rotary magnet 523 by the operation of that magnet, current sufficient to operate the locking contacts E of relay 501 130

or F of relay 532 might be induced in the left hand winding 526 of relay 525. To prevent the operating and locking of relay 501 or relay 532 by this induced current, their locking circuits are opened by the rotary magnet 523. The locking circuit for relay 501 may be traced from grounded battery 504, through winding 503 of relay 501, contacts E of relay 501, B of relay 515, B of rotary magnet 523 and contact B of relay 512, to ground at 514. The locking circuit for relay 532 may be traced from grounded battery 535, through winding 534 of relay 532, contact F of relay 532, contact B of rotary magnet 523, contact B of relay 512, to ground at 514. Both of these circuits are opened at contact B of rotary magnet 523 when it releases, thus preventing the locking of relays 501 or 532 should these relays be operated by induced current.

If wiper 542 reaches a bank terminal 543 connected to battery 437, that is to say, if it reaches a bank terminal associated with a calling line, relay 532 will be operated sufficiently to close its locking contact F. The operating circuit for relay 532 may be traced from battery 437 through winding of "cut-off" relay 438, contact B of line relay 436, test bank terminal 543, wiper 542, winding 533 of relay 532, contact B of relay 536A, left hand winding 526 of relay 525, contact A of relay 512 to ground at 514. When the locking contact F of relay 532 is closed, the lower winding 534 of that relay is energized and the relay then fully operates. The closure of the above circuit prevents relay 525 from releasing. This prevents further interaction between relay 525 and rotary magnet 523 which prevents further stepping of the latter.

40 "Cut-off" relay 438 establishes a holding circuit for itself, independent of line relay 436, which extends directly to the test bank contact 543 and to ground at 514 in the manner previously traced. The operation of relay 438 also opens the circuit of line relay 436 at contact C of the former relay and connects the station line 51 directly to wiper 546. When relay 436 releases, it in turn releases relay 554 unless another station in the same group of twenty lines is calling at this time. In this case relay 554 remains energized since it is common to each one of the twenty lines on the same level.

55 Relay 532 also opens a circuit to relay 501 so that its circuit as previously described is now opened at contact D of relay 532. A call from the station associated with 545 is thus prevented from interfering with the busy primary finder.

60 Relay 532 also establishes a circuit for operating relay 536A. This circuit may be traced from grounded battery 539 through winding 537 of relay 536A, contact C of relay 532, to ground 531 at "off-normal" contacts.

65 Relay 536A operates and closes a locking

circuit for relay 532 which prevents relay 532 from releasing when the rotary magnet releases. This circuit may be traced from battery grounded 535, winding 534 of relay 532, contact F of relay 532, contacts G and C of relay 536A, winding 526 of relay 525, contact A of relay 512 to ground at 514. When contact C of relay 608 (Fig. 5) closes, as described later, this circuit is grounded at 610, instead of at 514, thus holding the release lead 541 grounded when relay 512 releases.

75 Relay 536A also removes grounded battery 540 from relays 525 and 515 by opening its H contact and therefore releases these relays. It also removes ground from relay 512 by opening contact E, and switches start lead 553A from relay 512 through to the start lead 553B and the next finder switch.

80 Any further calls from this group of twenty customers' stations associated with the same relay 554 will be handled by the next idle primary finder. The circuit for starting the next idle finder associated with this group of twenty lines may be traced from ground 562, contact A of relay 558, contact A of relay 554, contact F of relay 536A, contact B of relay 536D to start lead of the next idle 85 finder.

90 When a primary finder is started by the group relay acting through the starting circuit of a prior finder switch, ground is placed not on the first test contact of the vertical commutator of the later switch, but on some higher contact. Which contact is grounded 95 depends on the place of the later switch in the series which lies between the "home switch" having the calling line on its first bank level and the last switch having the calling line on its tenth bank level.

100 The operation of relay 532 extends the line circuit 551 through to the selecting circuit 600 (Fig. 5). The line circuit 551 now extends (see Fig. 2) from ground 50 at the customer's station through the printer set, as previously traced to bank terminal 547, (Fig. 4), and thence through wiper 546, contact A of relay 501, contact A of relay 532, line 551, contact A of relay 601, (Fig. 5) winding of relay 603, contact A of relay 604, resistance 607 to grounded negative battery 606. Relay 603 115 is thereupon energized and operates slow release relay 608 which places ground at 610 on release lead 641, an extension of release lead 541 of the primary line finder. The operating circuit for relay 608 may be traced from grounded battery 609, winding of relay 608, contact B of relay 603, contact D of relay 601 to ground at 632.

120 Relay 536A also establishes a direct contact from ground at 610 of relay 608 of the selector circuit to wiper 542 of the primary finder, which keeps relay 438 operated when ground at 514 is removed from 541 by release of relay 512. This circuit may be 125 traced from wiper 542 through contact E of 130

relay 532, contact D of relay 501, contact C of relay 536A, release trunk 541, release trunk 641, contact C of relay 608 to ground at 610.

At the end of this sequence of operations relays 532 and 536A are held operated; the other relays of the primary finder are released.

If the calling line has been associated with the test bank contact 545 connected to wiper 544, relay 501 would have operated instead of relay 532. The operation of this relay causes it to close its locking contact E and to establish a locking circuit which has been previously traced. The operation of relay 501 also

switches the line circuit 551 from wiper 546 to wiper 548 and connects wiper 544 directly to contact B of relay 536A. Relay 536A upon operating connects the wiper 544 through its C contact to the release trunk

ground at 610 of the selecting circuit 600. Relay 501 also closes a circuit for operating relay 532 through its lower winding 534. This circuit may be traced from grounded battery 535 through winding 534 of relay 532, contact F of relay 501, contact C of relay 512, to ground at 531 of the "off-normal" contacts. Relay 532 then operates, causing the operation of relay 536A the functions of which have been previously described.

The interaction between the starting circuits of the various primary finders in a particular group remains to be described. These circuits are so arranged that the "home switch" of any calling line, if idle, will first be operated by an associated group relay 554 and also arranged so that no antecedent primary finder will take a call away from a subsequent finder by releasing when the latter has been operated but before it has found the calling line.

Each group of twenty customers' lines is associated with the relay 554. When a call is made by a customer, that relay starts the primary finder having on its first terminal bank level the group of twenty lines containing the calling line, provided this switch is idle. In other words, any call from a customer's station invariably starts the "home switch", if idle, but if that switch is busy, the relay 554 starts an idle one of the primary finders in the group to which the customer's line is multipled. As between the idle primary finders in the group, that finder will be started which has the group of twenty lines, containing the calling line, on the lowest bank level.

The start leads 553A, 553B, etc., lead to the group relays 554, which invariably when actuated start the "home switch" corresponding to the calling line, if the "home switch" is not busy. If the "home switch" is busy, the next idle switch is started over a circuit previously traced. If this next primary finder is also busy, the starting circuit will be extended in a similar manner to successive primary finders until an idle one is started.

Relay 536A has a locking winding 538 and similar locking windings are provided on relays 536B, 536C, etc., of the other line finders. If group relay 554 is operated at a time when line finder 500 is busy and therefore relay 536A is operated, a locking circuit will be closed for relay 536A, extending from grounded battery 561, through contact A of relay 560, winding 538 and contact D of relay 536A, contact A of relay 554 and contact A of relay 558 to ground 562. This locking circuit prevents relay 536A from releasing as long as group relay 554 is held energized by an incoming call not yet switched through the primary line finders. Similar locking circuits are provided for all of the primary line finders and serve to prevent any primary line finder that has been held operated by a prior call from releasing and then taking away a call from any other primary finder that has been started by a subsequent call before the latter has found the calling line.

Relay 536A has a contact A, which is connected in parallel with similar contacts D of the relays 536D, 536C, etc., of all the primary line finders serving the same group of two hundred lines. If any of the relays 536A, 536B, etc., of a particular group of line finders is not operated, the chain circuit through the contacts of these relays will be closed; while, if all of these relays are operated, this chain circuit will be broken. When the chain circuit is closed, relay 558 is energized over a circuit from grounded battery 559 through winding of relay 558, contact A of relay 536A, to ground at 562 or from battery 559, winding of relay 558, contacts D of relays 536 B, C, D, etc., whichever is closed, to ground at 562. When all of relays 536 A, B, C, etc., are operated, or in other words, when all of the primary finders associated with a particular group of two hundred customers' lines are busy, the circuits previously traced are opened at the contacts previously mentioned, and relay 558 is released.

The release of relay 558 removes ground at 562 from the group relay A contacts associated with start leads 553A, 553B, etc., of the primary line finders corresponding to a group of two hundred lines, since these group relay contacts are grounded in common at 562 through contact A of relay 558 as shown for relay 554, the other group relays being multipled as indicated at point 557.

If any line of a group of 200 should call at a time when all of the primary line finders corresponding to this group are busy, the group relay will therefore not ground the start lead. Consequently the locking circuits, for the relays 536A, etc., are opened, and where any finder in this group, of which a relay 536A, B, etc., is a part, becomes idle, that relay will release. When it releases the chain circuit will again be closed through its D contact, and relay 558 again operates.

The restoration of ground at 562 to contact A of relay 558 permits the idle switch to respond to another call from a customer's station.

If any part of the start leads 553A, 553B, etc., becomes grounded as a result of trouble in the circuit, the idle finders associated with the group of two hundred lines will start one at a time and if no lines are calling they will step up to the 10th level which is permanently grounded, and then rotate to the eleventh step, closing contact 505 which operates relays 532 and 536A. The operating circuit, for relay 532 may be traced from grounded battery 535, winding 534 of that relay, contact 505, contact C of relay 512 to ground 531 at the "off-normal" contacts. As there is no bank terminal such as 547 connected to wiper 546 however, and therefore the line circuit 551 is not grounded at 50 at a customer's station, relays 603 and 608 of the selecting circuit 600 are not operated. Moreover, since relay 608 does not operate there will be no ground on the release trunk 541, or 641, when relay 512 releases. Relay 536A remains locked through its lower winding 538 and the circuit previously traced. All other relays of the line finder release, however, and the release magnet 527 operates over a circuit previously traced to restore the switch to its normal position. When every one of the relays 536A, B, C etc., are operated, and relay 558 is consequently released, relay 560 will operate over a circuit from grounded battery 561, winding of relay 560, contact B of relay 558, to the grounded start lead. The operation of relay 560 by opening its contact A, removes battery 561 from the locking windings of the relays 536A, etc., permitting the relays of all idle finders to release. When the relays 536A, B, etc., are released, the trouble ground in the start lead will again operate each idle finder in succession. If any station is attempting to make a call at this time, the first finder to operate after the station calls will find the calling line. By means of relays 558 and 560 then, the primary line finders are accessible even when a start lead is improperly grounded.

Referring now to Fig. 5, when relays 438 and 532 (see Fig. 4) operate as previously explained, a circuit is closed for operating relay 603 which in turn operates relay 608. Resistance 607 is of such a value that the current in the line circuit will now be higher than the current previously flowing (see Fig. 2) through the dial lamp 70 from battery 433, through resistance 434, and the winding of relay 436 so that the dial lamp 70 at the customer's station is brightly lighted. This indicates to the customer that he may now dial to select the desired type of service.

When he dials, relay 603 operates and sends impulses through its B contact to hold slow

release relay 608 energized and through its A contact, contact B of relay 608 and "off-normal" contact 611 to operate relay 617 and the rotary magnet 616 in series. This rotary magnet is part of a simple ten point switch known as a "minor switch". This switch has two wipers 618 and 619 capable of rotating over the banks 633 and 634 respectively. As they rotate they are held by a holding pawl (not shown), but if the release magnet 614 is operated to release this pawl, the wipers may be returned to their normal positions by a spring (likewise not shown).

In response to the first impulses dialed, relay 617 and the rotary magnet 616 operate, the latter advancing the wipers 618 and 619 one step. This circuit may be traced from grounded battery 615, winding of rotary magnet 616, winding of relay 617, off-normal contact 611, contact B of relay 608, contact A of relay 603, contact D of relay 601 to ground at 632. The "off-normal" contacts operate, contact 611 opening and contacts 612 and 613 closing, on the first step of the wipers. The latter contacts remain closed until the wipers return to normal.

On the closure of the off normal contacts 613, the relay 604 is operated over a circuit extending from grounded battery 615, off-normal contact 613, winding of relay 604 to ground. The operation of this relay places resistance 605 in the line circuit, dimming lamp 70 of the customer's station, informing the customer that his line has not been extended through the secondary line finder. When the line circuit has been extended through the secondary finder the relay 601 operates, as will be later described, opening its A contact, and removing resistance 605 from the line circuit.

The opening of the "off-normal" contact 611 changes the impulse circuit. It now extends from ground at 632, contact D of relay 601, contact A of relay 603, contact B of relay 608, contact B of relay 617, windings of relay 617 and rotary magnet 616 to grounded battery 615. Relay 617 holds the circuit to both wipers open. After a group of impulses have been dialed and the wipers 618 and 619 have been rotated to the desired contact, relay 603 comes to rest energized. Relay 603 holds 608 energized and releases relay 617 and the rotary magnet 616. Relay 617 upon releasing closes its contacts A and C and thereby closes the circuits to both wipers. The upper wiper 618 now establishes a circuit from the test bank terminals 625 of an idle finder 700B in the selected group of secondary line finders to grounded battery at 602. This circuit may be traced from test bank terminals 625, conductor 620F, wiper 618, contact A of relay 617, winding of relay 601 to grounded battery 602. The

lower wiper 619 connects ground at 632 of relay 601 to the group relay 701B associated with the secondary line finder 700B which thereupon operates. This circuit may be 5 traced from ground 632, contact D of relay 601, contact B of relay 603, contact D of relay 608, contact C of relay 617, wiper 619, winding of relay 701B to grounded battery 702B. As in the case of relay 438 and primary finder 500, when the wiper of secondary finder 700B connects with bank terminal 625, relay 601 will operate. The operation of relay 601 opens its A contact, cutting resistance 605 from the line circuit, and extending the 10 line circuit through to the bank terminal of the secondary line finder.

The secondary line finder circuits are the same as those of the primary line finder except for a change in the wiring of the start 20 leads which is shown in Fig. 6. Parts of the secondary line finder similar to those of the primary finder, except where specifically numbered on the accompanying drawings, will be designated in the description by the 25 same reference characters. Each of these secondary line finders 700A, 700B, etc., serves to connect a receiving operator's printer set 800, etc., to any one of not more than two hundred trunks leading to the selecting 30 circuits as typified by 651. Each secondary line finder has four wipers and two two hundred point banks as in the case of the primary line finder (although only one pair of wipers is shown in the drawings). The selecting 35 circuit which has been previously described determines which group of secondary line finders, corresponding to a particular class to telegraphic service, is to start to find the trunk associated with the calling line. 40 As in the case of the primary line finders, ten relays 701B, etc., are provided, one for each group of twenty lines. These serve to ground the proper terminal associated with the vertical commutator wiper and to ground 45 the start lead for operating the relay 512 of the secondary line finder. Conductor 704 extends to the vertical commutator bank 506, and conductor 705 extends to the start lead 707, shown in Fig. 6.

50 The starting circuits for the secondary line finders are arranged as shown in Fig. 6. "Make-busy" keys or switches 726, 727, and 728, are provided for each secondary line finder. With these keys in their normal position, that is, against their A and C contacts 55 the common start lead 707 is adapted to start the first secondary finder in the selected group over start lead 753A. When this finder is busy, the common start lead 707 is extended to successive finders until an idle one is found and started. As all of the group 60 relays 701B, etc., are connected to this common start lead 707, instead of starting the "home switch" as do the group relays associated with the primary finders 500, these

group relays invariably start the first idle secondary finder in the selected group. With this arrangement, the first incoming call will always come to the first receiving operator associated with key 726 and with relay 736A. 70 If the first operator's printer is busy, the relay 736A will be energized and the start lead 707 will then be connected through to the secondary line finder associated with the second operator and so on until an idle operator is connected to the calling line. 75

Assuming that the first finder is busy and its relay 736A is operated, the circuit for reaching the next idle operator may be traced from the common start lead 707 which is connected to the ten relays 701A, 701B, etc., corresponding to a group of two hundred customer's lines, contact A of key 726, contact A of relay 736A, contact A of key 727, contact B of relay 736B to start lead 706B of the second associated finder. Assuming that the second finder is not busy it will therefore be operated under these conditions. When a group of printers is provided, the incoming traffic will be concentrated on the first printer 90 of the group during the least busy hours of the day. During the busy hour the first printers will be busy almost continuously and the subsequent printers will receive occasional calls as the traffic varies. This method of connection provides a convenient means for regulating the number of operators needed for handling the incoming traffic at different hours during the day. 95

If any operator's position is vacant the 100 corresponding make-busy key 726, 727, 728 etc., will be operated. For example, if the key 726 is operated and its B contact is closed the common start lead 707 is connected directly through to contact A of key 727 of the next secondary finder so that if this next finder is idle, it will be started in response to an incoming call. The C contact is also broken by this make-busy key 726, which has the effect of opening the branch of the chain circuit previously described in connection with Fig. 4, and has the same effect on this circuit that relay 736A, if operated, would have. It will be apparent that when contact C of key 726, therefore, is open and all of the other secondary finders corresponding to this group of two hundred trunks are busy, the relay 558 of the secondary finder start circuit will be released and ground removed from the contacts A of the group relays 701A, 110 701B etc., associated with start lead 707 permitting these relays to release when their associated switch becomes idle. 120

To repeat, when the secondary line finder 700B has found the calling selecting circuit, 125 an operating circuit for relay 601 is completed to ground 514 at the secondary line finder. The completion of this circuit causes relay 601 to operate, thereby extending the line circuit 551 through the selecting circuit 130

600, and causes the secondary finder to extend the line circuit to the receiving operator's set and the grounded battery 830. The line circuit may be traced from positive pole of the 5 grounded battery 831 associated with printer sending contacts 802, through winding 804 of relay 803, recall key 806, contact A of relay 532, contact A or B of relay 501 of the secondary line finder 700B, bank terminal 624, contact B of relay 601, contact A of relay 532, contacts A or B of relay 501, of primary line finder 500, wiper 546 or 548 and bank terminals 547 or 549 of this finder, contact B of cut off relay 438 and through the station 10 line circuit to ground at 50.

The direction of current flowing through the polar relay 58 (Fig. 2) at the customer's station is thereupon reversed. Since current flowing through this relay from battery 433 15 associated with line relay 436 and battery 606 associated with relay 603 has been in the negative direction, reversal of current through the polar relay causes the polar relay to close its A contact starting printer motor 93 as 20 previously described. The receiving operator's printer motor 820 is not started at this time, for its runs continuously and is controlled by the manually operated switch 823.

When the relay 736A of the secondary line 25 finder is operated, the release trunk 741 is grounded at 514 of the secondary finder over a circuit traced from negative battery 808, resistance 807, winding of relay 809, trunk 741, contact C of relay 736A, winding 526 of relay 525, contact A of relay 512 to ground at 514. Relay 809 at the receiving operator's 30 set is thereupon operated, closing contact 830, and substituting ground at 811 through key 810 for ground at 514 at the secondary line 35 finder. The operation of relay 809 also closes a circuit for the guard lamp 812 which may be traced from grounded battery 808, resistance 813, guard lamp 812, contact 830, key 810, to ground at 811. The lighting of the 40 guard lamp 812 informs the receiving operator that a subscriber has established connection with his set. Relay 809 also removes ground at 811 from the normally closed line 45 circuit 851 of the operator's set.

50 When the relay 512 of the secondary line finder, releases, ground at the secondary line finder connected to the release trunk 652 is released. This trunk, however, is now grounded at 811 through the contact 830 55 of relay 809 and the release key 810. The ground on the release key thus holds operated relays 536A, 532 and possibly 501 of both primary and secondary finder switches as well as relay 601, relay 809, and relay 438. The operation of relay 601 in extending the line circuit through to the secondary line finder removes ground 50 by the opening of contact A of that relay from relay 603 which releases 60 Relay 601 at its contact D also removes ground 632 and thereby releases relay 608,

and relay 701B. Relay 608 removes ground 610 from the release trunk 641.

Since the line circuit is now established between the printer of the customer's station and the printer at the receiving operator's 70 set, a customer may now send any message he desires. When the message has been received and acknowledged, the receiving operator opens release key 810. This removes ground from the release trunk 741, and releases relays 536A, 532 and possibly 501 of both finder switches and relay 601, 809 and 438. The restoration of the secondary finder switch 700B to normal releases relay 809 which closes the local circuit 851 through the 80 receiving printer. Relay 601 upon releasing operates release magnet 614 of the minor switch allowing its wipers 618 and 619 to be restored to normal. The circuit may be traced from ground 632, contact D of relay 85 601, contact A of relay 603, contact A of relay 608, winding of release magnet 614, off-normal contact 613 to grounded battery 615. Relay 438 upon releasing, causes negative current to pass through relay 436 from battery 433 thus reversing the station line current and stopping the printer motor 73. The release of the control relay 67 which also results from this reversal of current, removes a shunt from the high resistance winding 59 90 of the polar relay 58 and the line current is thereupon decreased so that the customer's station is now in its normal or idle condition.

The release of relays 532 of both finder 95 switches previously mentioned, closes the release magnet circuits of these switches and returns them to normal. The "off-normal" contacts are therefore restored to their normal positions as shown in the drawing and ground is thus removed from relays 536A and 105 501 of both finder switches. Upon their release, the circuit is now restored to normal.

If the calling subscriber should stop his own motor by the operation of the key 54 to "release position" in the manner previously 110 described, the receiving operator can operate for the recall switch 806, thereby substituting the positive potential on the line the negative potential of battery 814, through resistance 815. This reversal of current over 115 the line circuit releases the "release relay" 72 (see Fig. 2) at the called subscriber's station in the manner previously described. Then by restoring the recall switch 806, the positive 120 battery 830 is reconnected to the line, starting the subscriber's motor 73.

What is claimed is:

1. In a printing telegraph exchange system, a plurality of customers' stations, a printer at each of said stations, a central station, a plurality of printer groups at said central station, each furnishing a particular class of telegraphic service, means under control of any one of said customers' stations for selecting a particular group of said printers 125
- 130

- and automatic means for selecting an idle printer in said group.
2. In a printing telegraph exchange system, a plurality of customers' stations, a printer at each of said stations, a central station, a plurality of groups of receiving circuits at said central station, means under control of any one of said customers' stations for selecting a particular group of said receiving circuits and automatic means for selecting an idle circuit in said receiving circuit group.
3. In a printing telegraph exchange system, a plurality of customers' stations, a printer at each of said stations, a central station, a plurality of printer groups at said central station, each furnishing a particular class of telegraphic service, means under control of any one of said customers' stations for selecting a particular group of printers and automatic means for selecting the first idle printer in that group.
4. In a printing telegraph exchange system, a plurality of customers' stations, a printer at each of said stations, a central station, a plurality of printer groups at said control station, each furnishing a particular class of telegraphic service, means under control of any one of said customers' stations for selecting a particular group of printers, automatic means for selecting the first idle printer in that group, and means for making any printer inaccessible to said customer's station.
5. In a printing telegraph exchange system, a plurality of customers' stations, a printer at each of said stations, a central station, a plurality of groups of receiving circuits at said central station, means under control of any one of said customers' stations for selecting a particular group of receiving circuits and automatic means for selecting the first idle circuit in said group.
6. In a printing telegraph exchange system, a plurality of customers' stations, a printer at each of said stations, a central station, a plurality of groups of receiving circuits at said central station, means under control of any one of said customers' stations for selecting a particular group of receiving circuits, automatic means for selecting the first idle circuit in said group, and means for making any receiving circuit inaccessible to said customer's station.
7. In a printing telegraph exchange system, means for making printers inaccessible to calling stations, comprising a plurality of automatically operative switches, a start lead common to said switches adapted to start the first idle one of said switches, and means for making any of said switches busy in respect to said common start lead, comprising contact breaking means, individual to said switch, adapted to transfer said common start lead to the next one of said switches.
8. In a printing telegraph exchange system, a plurality of customers' stations, a central station, automatically operative and directly operative switches at said central station, a single line between each of said customers' stations and said central station, means under control of any one of said customers' stations for increasing the current in said single line, and means operable in response to said increase of current for actuating one of said automatically operative switches.
9. In a printing telegraph exchange system, a plurality of customers' stations, a central station, automatically operative and directly operative switches at said central station, a single line between each of said customers' stations and said central station, means under control of any one of said customers' stations for increasing the current in said single line, means operable in response to said increase of current for actuating one of said automatically operative switches, and means responsive to the operation of said switch for extending said single line to one of said directly operative switches.
10. In a printing telegraph exchange system, a plurality of customers' stations, a central station, automatically operative and directly operative switches at said central station, a single line between each of said customers' stations and said central station, means under control of any one of said customers' stations for increasing the current in said single line, means operable in response to said increase of current for actuating one of said automatically operative switches, and means responsive to the operation of said switch for extending said single line to one of said directly operative switches.
11. In a printing telegraph exchange system, a plurality of customers' stations, a printer at each of said stations, a central station, a plurality of printers and automatic switches at said central station, said automatic switches being adapted to interconnect one of said printers at said central station with a customer's station printer, a single line between said central station and each of said customers' stations, means under control of one of said central station printers for operating said switches, and means associated with a central station printer interconnected with a customer's station printer for increasing the current in the single line circuit over which said printers are connected.
12. In a printing telegraph exchange system, a calling customer's station, a central station, a normally unoperated line relay, a cut-off relay and an automatically operative switch at said central station, a single line

circuit including said line relay between said customer's station and said central station, means for increasing the current in said circuit to operate said line relay, means responsive to the operation of said line relay for actuating said switch, and means responsive to the actuation of said switch for operating said cut-off relay.

13. In a printing telegraph exchange system, a central station, a calling printer, automatic switches, a normally unoperated line relay and a cut-off relay at said central station, a called customer's station, a single line circuit including said line relay between said central station and said customer's station, means under control of said calling printer for actuating said switches, means responsive to the operation of said switches for operating said cut-off relay, and means responsive to the operation of said cut-off relay for breaking said circuit through said line relay, and completing a connection from said calling printer to said called customer's station.

14. In a printing telegraph exchange system, a plurality of customers' stations, a central station, a normally unoperated line relay and a normally unoperated cut-off relay at said central station individual to each of said customers' stations, a single line circuit between each of said customers' stations and said central station, means for operating both said line relay and said cut-off relay when one of said customers' stations is calling, and means for operating said cut-off relay alone when one of said customers' stations is being called.

15. In a printing telegraph exchange system, a customer's station, a central station, a receiving printer, a sending printer, incoming and outgoing switches at said central station, a single line between said customer's station and said central station, means for connecting said customer's station over said line and through said incoming switches to said receiving printer, and means for connecting said sending printer through said outgoing switches and over said line to said customer's station.

16. In a printing telegraph exchange system, means for connecting a sending printer at a central station to a customer's station, comprising in combination, a plurality of selector switches, a connector switch, a cut-off relay, and a single line between said central station and said customer's station.

17. In a printing telegraph exchange system, a customer's station, a central station, automatically and directly operative switches, and groups of receiving printers at said central station, a single line between said customer's station and said central station, and means under control of said customer's station for causing said automatically and directly operative switches to estab-

lish a connection from said customer's station, over said line, through said switches, to the first idle printer in a selected one of said printer groups.

18. In a printing telegraph exchange system, a customer's station, automatically and directly operative switches and groups of receiving circuits at said central station, a single line between said customer's station and said central station, and means under control of said customer's station for causing said automatically and directly operative switches to establish a connection from said customer's station, over said line, through said switches to the first idle receiving circuit in a selected one of said receiving circuit groups.

19. In a printing telegraph exchange system, a customer's station, a central station, a receiving printer and machine switches at said central station, a single line between said customer's station and said central station, means under control of said customer for actuating said machine switches to extend said single line to establish a communication circuit with said receiving printer, and means responsive to the operation of said switches for extending an independent circuit through said switches to said receiving printer to establish a release circuit, said release circuit being adapted to maintain the communication circuit, and being under the control of the receiving printer operator.

20. In a printing telegraph exchange system, a customer's station, a central station, a receiving printer at said central station, a communication circuit between said customer's station and said printer, an independent release circuit for maintaining said communication circuit at said central station, and means under control of the operator of said printer for breaking said release circuit and thereby dis-establishing said communication circuit.

21. In a printing telegraph exchange system, a plurality of customers' stations, a central station, a plurality of sending printers and switching apparatus at said central station, means under control of any one of said sending printers for operating said switching apparatus, means for extending by the operation of said switching apparatus three independent circuits through said apparatus and means for extending only one of said circuits to one of said customers' stations.

22. In a printing telegraph exchange system, a customer's station, a central station, a sending printer and switching apparatus at said central station, and means for operating said switches to extend a dial circuit and a release circuit through said switches, and a communication circuit from said sending printer to said customer's station.

23. In a printing telegraph exchange system, a customer's station, a central station,

a sending printer and switching apparatus at said central station, means for operating said switches to extend a dial circuit and a release circuit through said switches and to extend a communication circuit from said sending printer to said customer's station, said communication circuit being controlled by said release circuit.

24. In a printing telegraph exchange system, a customer's station, a central station, a sending printer and switching apparatus at said central station, means for operating said switches to extend a dial circuit and a release circuit through said switches and to extend a communication circuit from said sending printer to said customer's station, said release circuit being adapted to control said communication circuit, and means under the control of the operator of said sending printer to break said release circuit to dis-establish said communication circuit.

25. In a printing telegraph exchange system, means for extending a calling line to a predetermined group of automatically operative switches, comprising in combination, two associated relays, one responsive to dialing impulses and the other responsive to the operation of the first relay, a switch associated with said second relay and adapted to be operated by said first relay, a plurality of groups of automatically operative switches accessible through said switch, means for operating said relays to cause said switch to associate with a predetermined group of said automatically operative switches, and means responsive to the operation of said switch for actuating one of said automatically operative switches in said group.

26. In a printing telegraph exchange system, in combination, a selectively operative switch, a plurality of groups of automatically operative switches accessible to said switch, dialing means for causing said switch to connect with any of said groups, and means for preventing the actuation of a switch in one of said groups until said dialing means has fully operated.

27. In a printing telegraph exchange system, a plurality of customer's stations, a lamp at each of said stations, a central station, a selectively operative switch at said central station, a resistance associated with said switch, means for connecting said selectively operative switch and said resistance with said customer's station and thereby dimming said lamp.

28. In a printing telegraph exchange system, a plurality of customers' stations, a lamp at each of said stations, a central station, a selectively operative switch and an automatically operative switch at said central station, a resistance associated with said selectively operative switch, means for connecting said selectively operative switch and said resistance with said customer's station, thereby

dimming said lamp, means for causing said selectively operative switch to actuate said automatically operative switch, and means for removing said resistance from the customer's station connection when said automatically operative switch has been operated.

29. In a printing telegraph exchange system, a customer's station, a central station, an automatically operative switch and a cut-off relay at said central station, a line extending from said customer's station to said switch, another circuit extending from said cut-off relay to said switch, means for operating said switch to extend said line to said central station, a normally unoperated relay at said central station, means responsive to the operation of said switch for operating said relay and means responsive to operation of said relay for extending said other circuit to ground associated with said relay.

30. In a printing telegraph exchange system, a customer's station, a central station, a cut-off relay, an automatic switch, a receiving printer set and a relay at said central station, means for extending a release circuit from said cut-off relay to said automatic switch and means for operating said switch, under control of said customer's station, means responsive to the operation of said switch for energizing said relay, and means responsive to the operation of said relay for extending said release circuit to said receiving printer set.

31. In a printing telegraph exchange system, a central station, a printer at said station, a closed local circuit through said printer, a customer's station, automatic means for establishing connection between said customer's station and said central station printer, and means responsive to said interconnection for breaking said closed local circuit through said printer.

32. In a printing telegraph exchange system, a central station, a busy lamp and a plurality of selectors at said central station, means for testing a plurality of trunk terminals on a predetermined level of said selector, and means for increasing the current through said busy lamp when said trunks are busy, said means comprising a circuit closed by the rotation of the wipers beyond the last terminal tested for shunting a resistance from the busy lamp circuit.

33. In a printing telegraph exchange system, a plurality of customers' stations, printing telegraph equipment and driving means therefor at each of said stations, a central station, printing telegraph equipment and driving means therefor at said central station, a single wire closed circuit between said customers' station and said central station, automatic means for interconnecting the printing telegraph equipment at said customer's station and said central station, and means responsive to said interconnection for

starting the driving means at said customer's station.

34. In a printing telegraph exchange system, a plurality of customers' stations, a polar relay, printing telegraph equipment and driving means therefor at each of said stations, said polar relay being adapted to control the opening and closing of the circuit for said driving means, a central station, printing telegraph equipment and driving means therefor at said central station, a single wire closed circuit, including said polar relay, between said customer's station and said central station, automatic means for extending a connection including said polar relay from the printing telegraph equipment at said customer's station to that at said central station, and means responsive to said interconnection for reversing the current through said polar relay and thereby closing the circuit for the driving means at said customer's station.

35. In a printing telegraph exchange system, a customer's station having a printer motor circuit, a control relay operable to close said circuit and a release relay for de-energizing said control relay, a central station provided with machine switches for interconnecting said central station with said customer's station, means at the central station thereafter effective for energizing said control relay, and means under control of said customer's station for energizing said release relay.

36. In a printing telegraph exchange system, a customer's station, a printer having a printer motor at said station, a central station, automatic switches for interconnecting said stations, means at said central station thereafter operable for starting said printer motor, means under control of said customer's station for stopping said printer motor, and means at said central station for thereafter restarting said printer motor.

37. In a printing telegraph exchange system, a central station having a plurality of printer groups each furnishing a particular class of telegraphic service, a plurality of customer's stations, each having a printer, a motor for driving said printer and control means for starting and for placing said motor under the joint control of both of said stations, means under control of any customer's station of selecting a predetermined central station printer group, automatic means responsive thereto for selecting an idle printer in said group, means responsive to the selection of said idle printer for operating the control means at said customer's station, means under control of said central station for selecting any customer's station, and means under control of said central station for thereafter operating the control means at said customer's station.

38. In a printing telegraph exchange sys-

tem, a plurality of customers' stations, a central station, automatically operative and directly operative switches at said central station, a single line between each of said customers' stations and said central station, means under control of any one of said customers' stations for increasing the current in said single line, means operable in response to said increase of current for actuating one of said automatically operative switches, means responsive to the operation of said switch for extending said single line to one of said directly operative switches, said directly operative switch being thereafter operable from said customer's station to select one of a plurality of groups of automatically operable switches.

39. In a printing telegraph exchange system, a plurality of customers' stations, a central station, automatically operative and directly operative switches at said central station, a single line between each of said customers' stations and said central station, means under control of any one of said customers' stations for increasing the current in said single line, means operable in response to said increase of current for actuating one of said automatically operative switches, means responsive to the operation of said switch for extending said single line to one of said directly operative switches, said directly operative switch being thereafter operable from said customer's station to select one of a plurality of groups of automatically operable switches, and means responsive thereto for actuating the first idle switch in the selected group.

40. In a printing telegraph exchange system, a customer's station having a printer motor circuit, a control relay operable to close said circuit, a release relay operable to de-energize said control relay, and a polar relay operable in one direction to de-energize said release relay, a central station provided with machine switches for extending a line circuit including said polar relay to said customer's station, means at the central station thereafter effective for actuating said control relay, means at said customer's station for energizing said release relay without operating said polar relay, and means at the central station for subsequently operating said polar relay in a direction to de-energize said release relay, thereby re-closing said printer motor circuit.

In witness whereof, I hereunto subscribe my name this 22nd day of July 1930.

GILBERT S. VERNAM.

DISCLAIMER

1,895,113.—*Gilbert S. Vernam, River Edge, N. J.* AUTOMATIC TELEGRAPH SWITCHING SYSTEM. Patent dated January 24, 1933. Disclaimer filed June 5, 1934, by the assignee, *International Communications Laboratories, Inc.*

Hereby enters this disclaimer to that part of claims 14, 15, 20, 29, 30, 31, and 33 which is in the following words, to wit:

(1) He disclaims from claim 14:

“In a printing telegraph exchange system, a plurality of customers' stations, a central station, a normally unoperated line relay and a normally unoperated cut-off relay at said central station individual to each of said customers' stations, a single line circuit between each of said customers' stations and said central station, means for operating both said line relay and said cut-off relay when one of said customers' stations is calling, and means for operating said cut-off relay alone when one of said customers' stations is being called.”

(2) He disclaims from claim 15—

“incoming switches” when one thereof is an armature and its contact of a relay, and “outgoing switches” when one thereof is an armature and its contact of a relay.

(3) He disclaims from claim 20—

“In a printing telegraph exchange system, a customer's station, a central station, a receiving printer at said central station, a communication circuit between said customer's station and said printer, an independent release circuit for maintaining said communication circuit at said central station, and means under control of the operator of said printer for breaking said release circuit and thereby dis-establishing said communication circuit.”

(4) He disclaims from claim 29—

“another circuit extending from said cut-off relay to said switch”

except—

“another circuit extending from said cut-off relay to a stationary contact of said switch”

(5) He disclaims from claim 30—

“means responsive to the operation of said switch for energizing said relay”

except—

“electromagnetic means operating responsive to the operation of said switch to close an energizing circuit for said relay”

(6) He disclaims from claim 31—

“means responsive to said interconnection for breaking said closed local circuit through said printer”

except—

“electromagnetic means energized as a result of the establishment of said interconnection between the central station printer and the customer's station for breaking said closed local circuit through said printer”

(7) He disclaims from claim 33—

“means responsive to said interconnection for starting the driving means at said customer's station”

except—

“electromagnetic means energized as a result of the establishment of said interconnection of said printing telegraph equipment at the two stations for starting the driving means at said customer's station.”

[*Official Gazette June 26, 1934.*]
